SYSTEM FOR PRODUCING REFRIGERATION

Harry D. Edwards, Larchmont, N. Y., assignor to
The Linde Air Products Company, New York,
N. Y., a corporation of Ohio

Application November 20, 1933, Serial No. 698,794
In Cuba April 23, 1932

17 Claims. (Cl. 62—123)

This invention relates to a system for producing refrigeration, and more particularly to an improved method and apparatus for producing refrigerating effects by compressing and expanding air to be separated into oxygen and nitrogen constituents by rectification.

The invention has for its object generally an improved construction and arrangement of parts in gaseous cooling and/or separating systems which are efficient, economical and readily manufactured.

More specifically, the invention has for its object the provision of an arrangement, in which a gaseous medium is compressed, cooled and expanded, for utilizing the expansion to do external work for driving compression machinery in a manner which is advantageously reliable, efficient and economical in operation.

Another object is to separate the compression machinery which preliminarily compresses the gaseous medium to be supplied to refrigerating apparatus, such as that in which a liquefied gas is produced, into main compressing stages and boosting compressing stages and utilize expansion of at least a part of the compressed medium by doing external work to operate the boosting stages in a manner which tends to accommodate itself to changing loads without undue strain and waste.

It is also an object to provide a system for producing refrigeration having both throttling and engine expanding devices so constructed, related and proportioned that, when there is a tendency for the refrigeration effects of the throttling and engine expanding devices to become unbalanced and supply refrigeration in disproportionate amount, there is inherent capability in the system of restoring the balance, whereby the system provided is self-regulating.

Still another object is to provide a system of the character indicated with expansion means arranged to accomplish a part of the expansion by doing internal work or throttling and the balance by doing external work in a predetermined ratio to the former; arrangement being made to vary the expansion doing external work, automatically as also manually, to accommodate it to varying refrigeration and refrigeration requirements.

Other objects of the invention will in part be obvious and will in part appear hereinafter.

This application is a continuation in part of my copending application which issued May 29, 1934 as Patent No. 1,960,623.

The invention accordingly comprises the features of construction, combination of elements, and arrangement of parts, which will be exem-

plified in the construction hereinafter set forth and the scope of the application of which will be indicated in the claims.

For a fuller understanding of the nature and objects of the invention, reference should be had to the following detailed description taken in connection with the accompanying drawing, in which:

Fig. 1 is a schematic view partly in section and partly in elevation showing means for accomplishing thermodynamic operations on a gaseous medium used in producing refrigeration in accordance with the invention.

Fig. 2 is a fragmentary view showing in detail regulating mechanism of a character employed in conjunction with certain expansion machinery shown in Fig. 1; and

Fig. 3 is a fragmentary sectional view taken on the line 3—3 in Fig. 2.

The use of expansion engines for producing low temperatures is well known in the art of refrigeration, and it has heretofore been proposed to utilize the energy made available by the expansion of the medium supplied to such engine. No satisfactory arrangement, however, has been heretofore proposed for employing such engines in gas liquefaction systems of the present type, because the proper power distribution was not clearly recognized. In general, either the motive power available was not properly accommodated to variations in load, or a proper proportion of the load was not allocated to the expansion engine.

In the production of gases separated from the atmosphere, particularly in the production of oxygen, expansion engines, geared to various fixed loads, have been tried to provide some refrigeration. Changing conditions in the refrigeration to be provided, however, made the operation of such engines irregular and interruptions and cessation of service not infrequently occurred. Two different methods of gearing such engines to the load were, in general, practiced; for example, the engine was geared or belted to a compressor which was positively driven or assisted by an electric motor, or similar prime mover, so as to be run at a constant speed, or it was geared to drive an electric generator which was connected to a bank of lamps or other resistance load which wasted or dissipated the energy of expansion. In cases where the first method was practiced, the variations in the load imposed such service stresses on the gearing or belting that it was relatively short lived. In practice, the second method was generally preferred.

In the practice of the present invention, the compressing machinery is divided into a main part which does the main work of compression and into a boosting part which compresses to a still higher pressure than in the main part and has an expansion engine geared to drive the latter part, or "booster"; the energy for driving the main part being independently supplied. This permits the regulation of the expansion engine 10 to respond to variations in the refrigeration load as well as avoiding undue strains in the connection gearing. Also, in the preferred form, it is proposed to expand a part of the gas at high pressure by throttling at low temperatures to produce a high quality refrigerating effect under the Joule-Thomson principle, and to expand the balance through the expansion engine with external work usefully applied in the booster, to give a lower quality but large quantity refrigerating effect. In the system where the two effects are utilized, arrangements are provided to control the ratio between the volumes separately expanded, the two expansion means being operated in parallel. The present invention provides means for counteracting tendencies toward variation in speed of the booster-expander and to maintain a substantially constant refrigerating effect in the gases delivered by the system to a rectifying column. It also provides a balance in both respects automatically and in spite of variations in the conditions affecting the system. The factors which effect the accomplishment of these ends include, in the embodiment shown, a substantially constant rate of delivery from the main compressing means to the booster, the operation of the booster by other means, namely, an expansion engine device coupled to the booster and driven by the power produced in the expansion 40 of a portion only of the booster output, a ratio of expansion in the expansion engine substantially greater than the ratio of compression in the booster, and the maintenance of open and communicating passages from the outlet of the booster to the throttling valve and to the intake of the expansion engine, so that the pressure will rapidly equalize between these points.

There are inherent difficulties in obtaining the desired equalization in a system using a throttling valve, as here proposed, since the throttling valve may clog and interfere with the desired flow of gas into the rectifying column. Pressure within the passages which communicate with the throttling valve, in consequence, tends to rise and produce a slight increase in the power available to the expander. This tends to cause the expansion engine to increase its speed. However, the mechanical coupling would cause an equal tendency to increase the speed of the booster, which would tend to diminish the pressure in the gas which is being supplied to the booster at a constant rate and increase the ratio of booster compression. Thus the added work imposed upon the booster would absorb the tendency of the expander to increase speed and quickly and automatically restore the desired normal balance.

If, on the other hand, the flow of throttled gas is increased as, for example, by the removal of an obstruction, the first result is a reduced pressure in the lines which are connected with the throttling valve, and a slight reduction in the power available to the expander with a tendency for the latter to reduce its speed. Again, this tendency is offset by the mechanical connection 70 to the booster and the reduction in booster com-

pression ratio which always results when the speed of the booster is so reduced as to increase the pressure in the gas which is being supplied to the booster from the constant speed compressors.

In either case, the effect is to counteract any tendency toward a continuance of a departure from desirably balanced conditions. It is also seen that the system automatically adapts itself during these variations to deliver a desired predetermined refrigerating effect to the rectifying column. For example, any reduction in volume of throttled gas admitted to the column at high pressure is offset by increased pressure both in the throttled gas and in the expanded gas delivered from the expansion engine. The converse is equally true when the volume of throttled gas is increased.

Referring now to the drawing and particularly to Fig. 1, 10 denotes a first stage cylinder of a main compressor which effects a portion of the preliminary compression of the gaseous medium to be supplied to a gas liquefying and rectifying apparatus, shown generally at 30, the gaseous medium being supplied to the cylinder 10 by way of an inlet conduit 11 which conveys the gaseous medium from any suitable source, for example, from the atmosphere when filtered and cleaned. The gaseous medium when compressed in the cylinder 10 is discharged into a second stage compression cylinder 12, where the gaseous medium is further compressed, after which it is discharged to a third cylinder 13, where another stage of preliminary compression is accomplished, and finally to a cylinder 14 where a still further stage of compression is accomplished, the gaseous medium being thereby raised to a desired high pressure, for example, to 140 atmospheres, or approximately 2100 pounds gage pressure in the case of air. The pistons for the several stages of compression preferably have the same stroke but progressively decreased diameters, and are here shown on a common crank shaft 15, which has a fly-wheel 16 belted or otherwise geared to be driven from an electric motor 17. Interstage cooling is preferably practiced in connection with the conduits, which convey the compressed medium from one stage to another. For example, conduit 18 is shown as leading from the outlet chamber of the cylinder 10, the inlets and outlets of these stages being controlled in any suitable manner, for example, by poppet valves, one of which is shown at 19, such valves being actuated in any convenient manner, for example, by cams, the valve gear which accomplishes this actuation being omitted in the interests of clearness in the drawing. Coil 20 in the conduit 18 provides the heat transfer surface desired to cool the compressed medium sufficiently to be introduced in the inlet chamber of the cylinder 12. Similarly, a coil 22 provides the cooling surface in the conduit 21, which leads from the outlet chamber of cylinder 12 to the inlet chamber of cylinder 13. Similarly, a coil 24 provides cooling surface in the conduit 23, which leads from the cylinder 13 to the cylinder 14. A conduit 25 having a cooling coil 26 is arranged to convey the gaseous medium now at the desired pressure and temperature to the second part of the compression machinery.

The compression machinery to which the conduit 25 leads comprises a cylinder 27 for accomplishing further compression of the gaseous medium and boosts the pressure to a still higher value, for example, to a pressure of 200 atmospheres or approximately 3000 pounds gage in the

case of air. The compressed medium at this higher pressure in the preferred form shown is led, first, through a cooling coil 28 and, if desired, through moisture removal traps (not shown in the interests of clearness of illustration) and then divided into two portions, one being supplied through the conduit 29 through the heat exchanging means 29' for precooling this portion and through an expansion valve 29'' to column 30, 5 while the other is conveyed through conduit 31 to a cylinder 32, where expansion takes place by doing external work and is then supplied through the conduit 33 in parallel with that portion supplied through conduit 29 to the column 10 30. The desired quantity ratio to be generally maintained between the two portions is determined firstly, by the displacement of the expansion engine; secondly, by the time during which the inlet valve of this engine is open; and thirdly, 15 by the opening of the expansion valve 29''. For example, in the case of air, it is usually preferable that the expansion engine be of such capacity that it will expand 40% of the compressed air from the pressure of 3000 lbs. gage to the column 20 pressure of 75 lbs. gage for the production of the desired relatively large quantity of relatively lower quality refrigeration and that therefore 60% of the air will pass through conduit 29 to be precooled to a relatively low temperature by ex- 25 30 changer 29' and expanded through the expansion valve 29'' to obtain the desired high quality refrigeration within the column 30. The expansion means which thus does internal work with the compressed medium and the expansion engine 35 which does external work, operate in parallel and finally expand the medium to a relatively low pressure, for example, to a pressure of 5 atmospheres in the case of air, i. e., the medium thus expanded is supplied to column 30 at approximately 40 45 75 pounds gage pressure. It will be noted that the gaseous medium is here expanded in the expansion engine to a pressure materially lower than the pressure at which it is supplied to the compression cylinder 27.

45 In order that the expansion engine having cylinder 32 may do useful work, in accordance with the invention, this engine is coupled to drive the boosting compressor at 27. Any suitable mechanical connections that allow the expansion cylinder to operate expansively after admission cut off may be employed, for example, a system in which the pistons of the expansion engine and boosting compressor are connected by connecting rods 34 and 35, respectively, to a common crank 50 55 36, which has a fly-wheel 37. By this arrangement, the external work which the gaseous medium does in driving the expansion engine is transmitted to the boosting compressor 27. Column 30 is shown as provided with outlet connections 39 and 40, from which liquid and gaseous products are withdrawn, respectively, for example, a liquid rich in oxygen at 39 and a gas rich in nitrogen at 40.

60 65 By the arrangement shown, the main compressing stages run at a practically constant speed, thus discharging a substantially constant quantity of compressed gaseous medium. The motor 17 may accordingly be a substantially constant speed motor and supplies independently the energy required to drive the main compressing stages. The expansion engine on the other hand supplies power by which the boosting compressor is operated. In this manner, substantially all the work 70 75 done by the engine 32 is usefully employed in ac-

complishing the elevation of the gaseous medium to a higher pressure.

Where the refrigeration load tends to vary between very wide limits or where changes in the load to be normally carried are to be accommodated, it may be desirable also to provide manual adjustment for the admission valve mechanism. This may be conveniently provided in connection with the valve gear on shaft 41, that connects the crank 36 with the flywheel 37. This gear is shown 10 in Fig. 2 as comprising a cam 42 that actuates a reciprocating rod 43 having a cam wheel or roller 44 mounted in its end and bearing on the cam 42. The other end of this reciprocating rod has an articulated portion 45 which makes variable 15 engagement with a valve operating lever 46, the latter being pivoted at 47 to operate a spring closed poppet valve 48 mounted in the head of the expansion engine to control the admission of the compressed medium to be expanded. A valve 20 49 is also shown in the head of cylinder 32 for controlling the outflow into the conduit 33, and is actuated in any manner desired. In order that the articulated portion 45 may make variable engagement with the actuating lever 46, a cam roller 50 is pivoted in its end which bears against the arcuate cam surface 51 formed on the near side of the lever 46. Any suitable means for varying the position of the articulated portion 45 of the reciprocating rod in response to the refrigeration load may be employed, for example, an actuating lever 52 may be provided, which is pivoted on a frame 53 formed at the side of cylinder 32, and has an operating rod 54 which is moved in response to variations in such load; this movement may be effected manually or automatically, a manually manipulated nut 55 being here shown for locking the rod 54 in place.

55 In operation, it is seen that the gaseous medium which is to be compressed, cooled and expanded, 40 is drawn in from the atmosphere through the conduit 11 to the main compressing stages, where a desired high pressure is obtained, the energy for driving these compressing stages being delivered by the motor 17. The compressed gaseous 45 medium which has been subject to interstage cooling then passes through conduit 25 to the boosting compressor 27, after which it is divided into two portions, in accordance with the predetermined ratio, one portion passing by way of the conduit 29 through heat exchanging means 29' where it is pre-cooled by thermal contact with a cold product and through the throttling valve 29'' into the column 30, while the other portion 50 55 is passed by way of conduit 31 to the expansion engine 32, where the compressed gaseous medium delivers its energy to do external work and drive the boosting compressor 27, after which it is supplied through conduit 33 to the column 30; these portions being utilized together to accomplish the liquefaction and/or separation of gas in an economical manner in the column 30. Here, it is seen that the two expansion means, the first of which does internal work on the gas, while the second does external work, operate in parallel.

60 65 The proportion of high quality refrigeration to low quality-large quantity refrigeration may be changed through a relatively moderate range by adjusting the degree of opening of the inlet valve 48 on the expansion cylinder. Thus to effect an increase of this ratio, the articulated portion of the rod at 45 is moved outwardly from the cylinder head by causing the rod 54 to move inwardly. Thus, it is seen that the actuating stroke of the 70 75

lever 46 is reduced, so that the inlet valve 48 admits less compressed medium to be expanded. Consequently, less power is generated in the expansion cylinder, so that the engine will slow down slightly until a new balanced condition is reached. In practice, it is seldom necessary to adjust the ratio by means of the adjusting rod 54, as the fine adjustments to the demand for refrigeration are obtainable with the valve 29", 10 as well as automatically, as above described.

In a system of the present invention, a balanced condition is always automatically reached both when the proportions of air flowing are changed as described above and when there is 15 any change in the refrigeration load such as would be caused by slight obstructions at the expansion valve 29". It will be readily seen that a new balanced condition is automatically reached, since by reason of the mechanical coupling of 20 booster to expander, the constant rate at which gas is delivered from the initial compression to the booster, and the greater ratio of variation in booster work as compared with expander power with any given change in speed, any tendency for 25 the speed of the expansion engine to change is immediately taken up by the booster so that it adjusts itself and the power produced is equal to the power consumed. In the case of air, the ratio of expansion in the engine is

$$3000 \over 75 = 40;$$

the ratio of compression in the booster is approximately

$$3000 \over 2100 = 1.43.$$

If the throttling valve 29" should be closed slightly as by a slight obstruction, there is a 40 tendency for the pressure in conduit 31 to rise. If, for example, this pressure rises from 3000 to 3100, slightly more air will expand through a slightly increased expansion ratio, i. e.

$$3100 \over 75 = 41.$$

Consequently, the power output increases slightly and the speed would tend to increase. But at the booster cylinder, the mass per unit of time 50 of air handled is constant while the compression ratio change is at first

$$3100 \over 2100 = 1.475,$$

a proportionately much larger change in ratio, which requires increased power in the booster cylinder which tends to decrease the speed. These two tendencies balance at a speed which is only slightly different from the former. The 55 system is again stable at this speed for, if the expansion engine should tend to speed up, the power requirement of the booster would tend to increase at a greater rate, thus preventing the speeding up. Conversely, if the engine should tend to slow down, the power requirement of the booster will tend to fall off at a greater rate, thus preventing the slowing down. Friction can be neglected as it is practically constant within the range of operating conditions considered.

The inherent balancing tendency is the more positive when all the air passes through the booster cylinder and only a part of the air is expanded in the expansion engine, for then the expansion ratio can be sufficiently greater than 75 the compression ratio of the booster. For ex-

ample, when the proportion of air expanded through the expansion valve is 60% to 40% expanded in the engine, the inherent stability of the system is very great.

When the power output of the engine is decreased by decreasing the degree of opening of the expansion cylinder inlet valve, i. e., by providing an earlier cut-off, the engine tends to slow down, thus decreasing the displacement of the booster cylinder so that it can handle only 10 a smaller volume of air, but since the quantity or mass per unit of time of air being delivered by the main compressor is practically constant, the pressure in conduit 25 of air entering the booster will rise so that its volume is decreased 15 to a value equal to the decreased displacement of the booster. Compression, therefore, occurs through a smaller compression ratio and less power is used by the booster, while more work is thrown upon the main compressor.

The use of a coupled booster-expander as here proposed permits more economical starting. At the beginning of operation, it is desirable to speed up the cooling of the apparatus and the condensing of considerable air which are pre- 25 requisite to rectification. Therefore, at the beginning it is necessary to provide a relatively great refrigerating effect even at the expense of high quality. This is accomplished in practice by passing a relatively large quantity of air 30 through the engine until the apparatus reaches the exhaust temperature of the engine, then switching to the ratio of engine expanded to throttled air which gives a desired Joule-Thomson cooling and is not far from the usual operating 35 point.

Since the dimensions of the expansion engine are fixed, increasing the amount of air to the engine results in lowering the ratio of expansion and increasing the pressure and temperature at 40 the point of exhaust, and the temperature of the exhaust gas leaving the engine. In the booster-expander the speed increases with the larger cut-off, so that the cut-off does not have to be quite so great to handle a definite increase in 45 volume. Consequently, the exhaust temperature of the booster-expander engine is lower than that of a constant speed engine. Thus during the first period of starting up, more heat is removed per pound of gas processed, and also the 50 first period is continued to slightly lower temperature which is more economical because engine cooling is more efficient than Joule-Thom- son cooling.

The stabilization effect operates to neutralize 55 substantially any disturbance arising because of the fact that the opening at the orifice of valve 29" changes slightly from hour to hour. Such changes are produced by carbon dioxide snow and possibly some water snow forming on and 60 then flaking off the valve. When, due to flaking off of such snow, a slight additional opening of the valve 29" occurs in a cycle in which an expansion engine runs at constant speed, the head pressure falls, and since the amount of air through the expansion engine is directly proportional to the suction pressure and the speed, it also falls. Thus the ratio of the amount of engine expanded air to throttled air may fall 65 markedly. However, in the case of the self- 70 governing booster-expander, a drop in the high pressure, causes the engine to speed up since the ratio of compression is decreased more than the ratio of expansion. This increase in speed compensates for the decrease in pressure. Both 75

paths for the air, that is, those through conduits 31 and 29 respectively, are opened, and the ratio of engine expanded to throttled air is maintained more nearly constant. This constant ratio of high to expanded air which is obtained by the use of the booster-expander has a marked effect in securing a stable operation.

The boosting compressor and expansion engine may be designed from the engineering data generally applicable to machines of their kind. The volume of gaseous medium to be handled through the two machines being assumed, together with the pressure change across each, the boosting compressor and expansion engine can be built of such size as to run at any predetermined speed. The highest pressure in the system, which is reached between the boosting compressor and the expansion engine, is an important datum, and must be of the proper degree in order that the system may operate as intended. The system has been proved to be inherently stable, and if the piston displacement of the boosting compressor, and that of the expansion engine are of the proper magnitude, all pressures and speeds remain substantially constant at their intended values.

Since certain changes may be made in the above construction and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent, is:

1. The method of compressing and expanding a gaseous medium to produce a liquefied gas which comprises compressing the gaseous medium at a substantially constant rate by means of energy independently supplied, further compressing the compressed medium at a rate which may vary, dividing said further compressed medium in two portions, expanding said portions by doing internal work and external work respectively whereby liquefaction results, utilizing the external work in effecting said further compression, and automatically maintaining the volume of the medium liquefied substantially constant 50 when the ratio of the portion expanded internally to that expanded externally changes.

2. The method of compressing and expanding a gaseous medium to produce a liquefied gas which comprises compressing the gaseous medium at a substantially constant rate by means of energy independently supplied, further compressing the compressed medium at a rate which may vary, cooling the compressed medium by heat exchange, engine expanding at least a portion of the compressed medium, utilizing the energy obtained from said engine expansion to do the work of said further compression, throttle expanding the remaining portion of the compressed medium, and counteracting the effect of an interference with the rate of throttle expansion to change the volume of gaseous medium liquefied by changing the rate at which said work is done.

3. The method of compressing and expanding a gaseous medium to produce a liquefied gas which comprises compressing the gaseous medium at a substantially constant rate by means of energy independently supplied, further compressing the compressed medium at a rate which may vary, cooling the compressed medium by heat exchange, dividing said cooled compressed medium

into two parts in accordance with a desired ratio, effecting throttling expansion of one of said parts, engine expanding the other part, utilizing the energy obtained from said engine expansion to do the work of said further compression, and automatically changing the rate at which said external work is utilized in response to changes in the rate at which said throttling expansion takes place whereby the volume of the medium liquefied remains substantially constant. 10

4. The method of compressing and expanding air in a system having compression devices arranged in series and expansion devices arranged in parallel for producing a refrigerating effect which comprises compressing the air drawn from the atmosphere at a substantially constant rate, cooling the same by heat exchange, further compressing the cooled compressed air at a rate determined by a predetermined pressure differential in the system, further cooling the same by heat exchange, dividing said further cooled compressed air into two portions in accordance with a predetermined ratio, further cooling one of said portions by causing the same to expand and to do internal work, further cooling the other of said portions by expanding the same and causing the same to do external work, the ratio of expansion for said last-mentioned portion being substantially greater than the ratio of compression accomplished when effecting said step of further compression, supplying energy independently to accomplish the compression at said constant rate, applying the energy released by having one of said portions do external work for accomplishing the step of said further compression, and compensating any tendency to change the ratio of the portion expanded by doing internal work by a correlated tendency in the portion expanded by doing external work whereby the volume of liquefied medium produced remains substantially 35 constant.

5. The method of compressing and expanding a gaseous medium to produce a refrigerating effect which comprises supplying independently the energy for effecting the step of initially raising the pressure of a gaseous medium from an initial low pressure to a relatively high pressure, cooling the same by heat exchange, boosting the pressure of said compressed medium to a still higher pressure, again cooling the medium by heat exchange, dividing said compressed medium into two portions and expanding the same in parallel by causing the same to do internal and external work respectively, applying the energy released in doing external work to accomplish 45 the step of boosting the medium to said higher pressure, and utilizing a variation in pressure which is a function of said boosting compression to determine the relative amounts of energy to be applied in effecting said boosting compression 55 with respect to said initial compression whereby tendencies to variation in the effect desired are counteracted.

6. The method of delivering compressed cooled air to a rectifying column, which comprises preliminarily compressing and cooling input air, further compressing at least a portion of said input air, indirectly cooling said further compressed air, expanding at least a portion of said input air with internal work through a throttle valve 70 into the column, expanding at least a portion of said input air with external work through an expansion engine into the column, utilizing said external work for said further compressing, and automatically maintaining the volume and re- 75

frigerating effect of input air to the column substantially constant despite fluctuation in the ratio of input throttled air to total input air.

7. The method of producing refrigeration in a system having compression devices and engine expansion and throttling expansion devices in parallel for processing air supplied to a rectifying column, which comprises compressing air drawn from the atmosphere to a desired high pressure by means of energy obtained from an external source, boosting the pressure of said compressed air by means of energy obtained from the engine expansion of a portion of said compressed air, effecting throttling expansion of the remaining portion of said boosted compressed air, and proportioning the expansion ratio by which said engine expanded air is expanded to the compression ratio by which the boosting of said compressed air is effected to have a value such that any tendency for the total air and refrigeration input to the column to vary, on account of some interferences with the free flow of throttled air to the column, is compensated for and a self-balancing system is obtained.

8. The method of producing refrigeration in a system having compression and expansion devices arranged to process air supplied to a rectifying column, which comprises initially compressing air to a desired high pressure, thereafter boosting all of said compressed air to a still higher pressure, dividing said boosted compressed air into a plurality of portions, causing one of said portions to expand and do internal work, causing another of said portions to expand and do external work, utilizing said external work to effect said boosting compression, and proportioning the expansion ratio of doing external work to the ratio of the boosting compression so as to have a value such that any tendency for the total air and refrigeration input to the column to vary, on account of interference with internal work, is compensated for over the range of normal operation.

9. The method of producing refrigeration in a system having compression devices arranged in series and expansion devices arranged in parallel to process air supplied to a rectifying column, which comprises compressing the air in said series of compression devices to successively higher pressures, providing independently the energy for operating all except the final of said compression devices, expanding portions of the air drawn from said final compression device by causing the same to do internal and external work respectively, utilizing the external work done by said expanded portions to drive said final compression device, proportioning the expansion ratio when doing external work to the ratio of the final compression device so that any tendency for the total refrigeration input to the column to change, due to changes in the expansion accomplished by said internal work expansion devices over the normal range of operation is compensated for, and manually adjusting the external work expansion devices to accommodate changes which are beyond the range of normal operation.

10. The method of producing refrigeration in a system having compression devices and engine expansion and throttling expansion devices in parallel for processing air, which comprises compressing the air to a desired high pressure by means of energy obtained from an external source, boosting the pressure of all of said compressed air by means of energy obtained from expansion of said compressed air, initially cooling said system by engine-expanding a greater than

normal proportion of said boosted compressed air, and when cooled to a desired low temperature simultaneously expanding in normal proportion different portions of said boosted compressed air by engine expansion and throttling expansion respectively.

11. The method of producing refrigeration in a system having compression devices and engine expansion and throttling expansion devices in parallel for processing air, which comprises compressing the air to a desired high pressure by means of energy obtained from an external source, boosting the pressure of all of said compressed air by means of energy obtained from expansion of said compressed air, initially cooling said system by engine expanding a greater than normal proportion of said boosted compressed air, and when said system is sufficiently cooled, switching to normal proportions the respective portions of said boosted compressed air to be expanded by throttling expansion and engine expansion in parallel.

12. In a system for producing refrigeration by processing atmospheric air, the combination comprising means for compressing intake air at a substantially constant rate, a booster compressor arranged for operation at a variable speed for further compressing the compressed air, a throttling valve for expanding a portion of said further compressed air, an expansion engine for expanding another portion of said further compressed air in parallel to that expanded in said throttling valve, said expansion engine having a ratio of expansion substantially greater than the ratio of compression in said booster compressor, and a mechanical coupling connecting said expansion engine to drive said booster compressor whereby said booster compressor and said expansion engine are able to absorb any tendencies to variation in the power requirements of said booster compressor when the flow of air through said throttling valve is interfered with.

13. In a system for producing refrigeration by processing atmospheric air, the combination comprising main compressing means for compressing air drawn from the atmosphere, means for driving said main compressor, an additional compressor connected in series with said main compressor for boosting the pressure of all of the air compressed in said main compressor to a higher pressure, a throttling expansion device and an engine expansion device disposed in parallel, each arranged to receive a portion of the air compressed to said higher pressure and supplying the same to a common place where said refrigerating effect is produced, means for coupling the engine expansion device as the sole driving means to drive said boosting compressing means, and means responsive to a pressure variation which is a function of said boosting compressor for determining the energy to be supplied respectively to said first named and to said second named driving means whereby to maintain substantially constant a desired effect at the place of use.

14. In a system for producing refrigeration, the combination with an apparatus for processing atmospheric air, having a main compressing means for initially compressing the air to a desired high pressure, of additional compressing means for boosting air compressed in said main compressor to a higher pressure, a heat exchanger, engine means for expanding said air compressed in said system by doing external work and decreasing the pressure to a value less than said

- desired high pressure, means for conveying the air subsequent to compression through said heat exchanger to a place of use, means for applying the work of said engine expanding means to drive said additional compressing means, means for regulating the speed of said engine expanding means, and power means for independently supplying energy to drive said main compressing means.
10. 15. In a system for producing refrigeration, the combination with an apparatus for processing atmospheric air having a main compressing means for initially compressing the air to a desired high pressure, of boosting compressing means for raising the compressed air to a higher pressure, throttling expansion means, engine expansion means, means for dividing and conveying the air at said higher pressure from said boosting compressing means to said throttling expansion means and to said engine expansion means respectively into portions in accordance with a predetermined ratio, means for mechanically coupling said boosting compressing means to said engine expansion means for utilizing the work done by expansion, said engine expansion means having a relatively large expansion ratio and said boosting compressing means a relatively small compression ratio, whereby said coupled boosting compressing means and the engine expansion means are inherently capable of absorbing tendencies for speed variation due to variation of pressure on the intake side of said boosting compressing means.
15. 16. In a system for producing refrigeration, the combination with an apparatus for processing atmospheric air having a main compressing means for initially compressing the air to a desired high pressure, of boosting compressing means for raising the compressed air to a higher pressure, a heat exchanger for receiving the air from said boosting compressing means, engine expansion means for expanding a portion of said boosted compressed air, throttling expansion
- means for expanding another portion of said boosted compressed air, means for dividing the air received from said heat exchanger into two portions in accordance with a predetermined ratio, engine expansion means for expanding one of said portions, throttling expansion means for expanding the other of said portions, means for mechanically coupling said engine expansion means to drive said boosting compressing means, said coupled boosting compressing means and engine expansion means having their respective displacement ratios relatively proportioned so as to provide a system capable of compensating for any tendency to variation due to changes in the amount of air being processed by throttling expansion over the normal operating range, means for regulating the speed of said engine expansion means beyond the normal range of variation, and power means for independently supplying energy to drive said main compressing means.
20. 17. In a system for producing refrigeration by processing air, the combination comprising a main compressing means for compressing air at a substantially constant rate, additional compressing means for boosting the pressure operating at a variable rate, means for effecting throttling expansion of a portion of the air, the pressure of which has been boosted, means for effecting engine expansion of another portion of said boosted compressed air arranged to operate in parallel with said throttling expansion means, said engine expansion means normally effecting expansion by a greater ratio than the ratio of compression in said additional compressing means, and a coupling arranged to transmit driving energy from said engine expansion means to said additional compressing means whereby the coupled means absorbs any tendency to variation in the power requirements of said additional compressing means when additional resistance develops to the flow of air through said throttling expansion means.
